SPARE TIRE ADVERTISING SIGN

Filed Feb. 1, 1927

UNITED STATES PATENT OFFICE.

ROY ARTHUR TARIEL, OF SACRAMENTO, CALIFORNIA.

SPARE-TIRE ADVERTISING SIGN.

Application filed February 1, 1927. Serial No. 165,087.

This invention relates to a spare tire advertising sign.

The object of the invention is the construction of a simple and efficient sign, especially adapted for use on the side of a spare tire cover.

Another object of the invention is the construction of a sign that has removable "slides," for increasing the advertising efficiency of the sign, said sign being peculiarly constructed for applying the same to the cover of a tire.

With these and other objects in view, my invention comprises certain novel constructions, combinations and arrangements of parts as will be hereinafter fully described, illustrated in the accompanying drawings, and more particularly pointed out in the appended claims.

10 In the drawings:

Figure 1 is a view in front elevation of a sign constructed in accordance with the present invention.

Figure 2 is a sectional view taken on line 2—2, Figure 1, and looking in the direction of the arrows.

Figure 3 is an enlarged fragmentary, sectional view taken on line 2—2, Figure 1, and looking in the direction of the arrows.

Figure 4 is a plan view of one of the outer transparent slides.

Figure 5 is a plan view of the central transparent slide.

Referring to the drawings by numerals, 1 designates the spare tire cover, constituting supporting means to the outer face or side of which is detachably secured the sign 2. This detachable securing of sign 2 to the side of cover 1 is permitted by means of the fastening devices 3. These fastening devices 3 comprise a rotatable stud 4 fastened to the cover 1, and extending through metal eyelets 5.

The detachable sign 2 comprises a disc like fabric body 6, such as imitation leather, and encased in the edge of this body 6 is a ring like rod 7. This rod 7 acts as a frame or stiffening element to the sign and gives stability and rigidity to the entire body. The metallic eyelets 5 are fastened to body 6 contiguous to rod frame 7, as shown in Figures 2 and 3.

The body 6 is provided with preferably three openings covered by the transparent or celluloid upper slide 8, central slide 9 and lower slide 10. Upper and lower slides 8

and 10 are similarly constructed. The openings in the body 6 produce strips 11, and on these strips 11 are fastened intermediate brackets 12. This fastening is accomplished by rivets 13, extending through the body of the bracket and through the strips 11. Each bracket 12 comprises a body 14 (Fig. 3), terminating at its upper and lower edges in substantially U-shaped flanges 15, into which the slides are placed. On the outer edge of the outer openings I place upper bracket 16, and lower bracket 17. Each of these brackets 16 and 17 comprises a body 18, Figure 3, through which extend rivets 19, and these rivets also extend through portions of the body 6. The body 18 is provided on its outer edge with a U-shaped flange 20, into which is slid an edge of a slide.

The central celluloid slide 9 is provided with end tongues 21 that are slid in behind body 6, as shown in dotted lines in Figure 1, and its edge tongues 22 are slid or "sprung" into the receiving flanges of the contiguous brackets. Each of the upper and lower slides 8 and 10 is provided with end tongues 21, performing a like function to tongues 21 of slide 9. Each of these slides 8 and 10 is also provided with edge tongues 22 similar in structure and in function to tongues 22. It will, therefore, be seen that by pushing slightly outward on either one of the slides, it can be slid or sprung out of its holding brackets, but when no manual pressure is on the slide, it will be efficiently retained upon the body 6 by the "interlocking" action of the edge and end tongues, positioned in the metal brackets and also behind portions of the body at the ends of the viewing openings.

On these slides 8, any kind of advertising printing or painting may be exposed, and at night an electric bulb can be placed behind the sign, within the spare tire, efficiently illuminating the sign for the maximum amount of advertising results.

I use the term "slide" in a broad sense to designate the celluloid sheets upon which the sign is exposed.

While I have described the preferred embodiment of my invention and illustrated the same in the accompanying drawing, certain minor changes or alterations may appear to one skilled in the art to which this invention relates during the extensive manufacture of the same, and, I, therefore, re-

serve the right to make such changes or alterations as shall fairly fall within the scope of the present invention.

What I claim is:

- 5 1. In a device of the class described, the combination of a spare tire cover provided with fastening devices all around one side thereof, a detachable sign mounted on said fastening devices, and said sign provided
- 10 with ring-like reinforcing means near said fastening devices.

2. In a device of the class described, the combination of a spare tire cover, provided with fastening devices all around the outer face thereof, a disc-like sign against the outer face of said spare tire cover and detachably mounted on said fastening devices, and said sign provided with a metallic ring enclosed in its outer edge.

In testimony whereof I hereunto affix my signature.

ROY ARTHUR TARIEL.
